By James L. Norris.
Attest,*

UNITED STATES PATENT OFFICE.

ROBERT ADAMS, OF SOUTHWARK, COUNTY OF SURREY, ENGLAND.

DEVICE FOR OPERATING TRANSOMS, SKYLIGHTS, &c.

SPECIFICATION forming part of Letters Patent No. 351,147, dated October 19, 1886.

Application filed March 25, 1886. Serial No. 196,596. (No model.) Patented in England December 22, 1884, No. 16,817.

To all whom it may concern:

Be it known that I, ROBERT ADAMS, a subject of the Queen of Great Britain, residing at 17 Blackman street, Southwark, in the county 5 of Surrey, England, engineer, have invented certain new and useful Improvements in the Method of Opening and Closing Fan-Lights, Skylights, Ventilators, and Analogous Articles, and in the fittings and appliances in connection therewith, (for which I have obtained a patent in Great Britain, No. 16,817, dated December 22, 1884,) of which the following is a specification.

This invention has for its object to provide 15 novel and simple devices for opening and closing hinged skylights, fan-lights, ventilators, and analogous appliances; and it consists in the construction and combination of devices hereinafter described and claimed, reference 2 being made to the accompanying drawings, in which—

Figure 1 is a sectional elevation showing the invention applied to a fan-light hinged at the bottom. Fig. 2 is a similar view showing 25 a variation in the arrangement of the parts, and Fig. 3 a detached view of the slotted link and pawl-and-ratchet devices shown in Fig. 1.

In order to enable those skilled in the art 30 to make and use my invention, I will now describe the same in detail, referring first to Figs. 1 and 3, where the letter *a* indicates a fan-light hinged at its lower end, as at *a'*, to the fan-light frame *e*. The letter *c* indicates a metallic or other suitable case mortised in one edge of 35 the fan-light and containing a shaft, *f*, having a crank-arm, *g*, carrying a pawl, *h*, which is located outside the case. To the shaft is attached an arm, *d*, having an eye, *d'*, for the attachment of a cord, chain, or rod, *d''*, so that 40 by pulling the cord the shaft will be rocked and the pawl moved against the tension of a spring, *i*, which restores the pawl to its nor-

mal position when the cord is released. A link, *b*, is pivoted at one end to the fan-light frame, as at *b'*, and at its other end is provided 45 with a longitudinal slot, *b''*, having closed end walls, *b''*, and a ratchet, *b'''*, at one side, with which the pawl engages and disengages for adjusting the fan-light to any required position. If the fan-light be entirely closed, the 50 link *b* folds up with it in the fan-light opening, as will be obvious.

The pawl may be operated otherwise than by a cord, chain, or rod, and the spring may be dispensed with, if desired.

In Fig. 2 the construction is the same, the arrangement being simply reversed—that is, the slot *b''*, with its closed end walls, *b''*, and ratchet-edge *b'''*, are formed in a bracket secured to the fan-light, and the link *b* carries the hereinafore-described spring-pawl *h*, operating-shaft *f*, and arm *d*.

The fan-light shown in Fig. 1 is readily closed by simply pushing or pulling it upward, while that shown in Fig. 2 is opened in a similar 65 manner.

Having thus described my invention, what I claim is—

The combination, with a fan-light or analogous device, hinged as shown, of a link, *b*, pivoted at one end to the frame and having a slot 70 at the other end, provided with the ratchet *b'''* and closed end walls, *b''*, the pawl *h*, for engaging the ratchet, a lever, *d*, for operating the pawl, and a case for the lever and pawl on 75 the fan-light, substantially as described.

Dated this 4th day of March, 1886.

ROBERT ADAMS.
